CLARENCE J. COBERLY, OF LOS ANGELES, CALIFORNIA, ASSIGNOR TO KOBE, INC., OF LOS ANGELES, CALIFORNIA, A CORPORATION OF CALIFORNIA

AUXILIARY JET CUTTING TIP FOR CUTTING TORCHES AND METHOD OF USING SAME

Application filed September 29, 1923. Serial No. 665,645.

My invention relates to the art of cutting slots in metal plates, and is particularly applicable to the cutting of slots in oil well casing.

5 In the production of oil, it is generally necessary to provide a steel casing or pipe which extends from the surface of the earth down into the oil sands, and which is perforated where it extends into the oil sands with slots 10 sufficiently narrow to hold back the coarse sand and gravel surrounding the pipe, while at the same time permitting the oil to flow therethrough. I have found that slots suitable for this purpose can be economically 15 produced by a cutting torch, using an oxygen flame.

It is highly desirable to produce slots having a keystone-shaped section. That is to say, it is desirable to produce a slot having a 20 uniform width at the outer surface of the pipe, which slot is wider at the inner surface of the pipe, it having been found that slots having this shape are less likely to clog up in the operation of the well. My invention 25 provides a ready means for cutting slots of this peculiar form in the casing before it is put into the well.

Further objects and advantages will be made evident hereinafter.

30 Referring to the drawing which is for illustrative purposes only,

Fig. 1 is a cross section through a form of cutting tip adapted to carry on my invention.

35 Fig. 2 is a section on a plane represented by the line 2—2 of Fig. 1.

Fig. 3 is a section of the slot produced.

In the form of invention illustrated in these drawings, 11 is a cutting tip having a conical head 12, which is seated in the torch in the usual manner. The tip 12 is preferably provided with a counterbored orifice 13, extending for a considerable distance into the body of the tip 11, two divergent cutting orifices 14 extending downwardly from the bottom of the counterbore portion 13. Four heating orifices 15 are provided and the torch is so arranged that oxygen is supplied to the passage 13 and to the orifices 14 and a mixture of combustible gas and oxygen is supplied to

the heating orifices 15. For cutting ordinary oil well pipe having slots $\frac{3}{16}$ inch wide at the outside and $\frac{1}{16}$ inch wide at the inside of the casing, I provide heating orifices 15 which are .024 inch in diameter and I provide cutting orifices 14, .028 inch in diameter, the angle between the orifices 14 being about 7 degrees. I have found, however, that the use of only the two orifices 14 tends to cut in the form shown in Fig. 3, leaving a tongue or core 20 along the middle of the slot. For the purpose of eliminating this core and thus speeding up the operation, I provide an orifice 21 which directs the flame centrally into the slot in the general direction of the dotted lines 22 of Fig. 3, thus tending to reduce the core 20. By the use of the auxiliary or core cutting orifice 21, I am able to economically produce wide slots in oil well casing.

Slots having a keystone shape have a 70 special utility in oil well casing, as any material passing into the slot through the narrow outer opening will then pass entirely through the slot without clogging it.

By forming the slots with a jet of definite 75 form, it is possible to form a slot of uniform width and form throughout its length.

By adding additional core cutting orifices, any width of slot desired may be produced.

I claim as my invention:

1. The method of cutting a slot having inwardly and downwardly divergent side walls which comprises: heating the metal to be cut, directing against said metal two cutting jets spaced transversely of the desired slot and relatively diverging outwardly to produce the angled side walls of said slot, directing a third cutting jet between said two cutting jets to attack the intermediate metal between said side walls, and moving all of 80 said jets relative to said metal.

2. The method of cutting a slot having inwardly and downwardly divergent side walls which comprises: heating the metal to be cut, directing two relatively diverging cutting jets to attack the metal at points relatively spaced transversely of the desired slot, directing an auxiliary cutting jet to attack the metal between said points, and moving all of 95 said jets relative to said metal.

3. A method of cutting a slot in a metal member, the walls of which slot have a given angular relation, which consists in heating a given area of said metal member, directing a pair of jets through said metal in said heated area, the axes of said jets being substantially parallel with the planes of the desired walls of said slot, moving said jets in said heated area to form said walls and produce a tongue of metal projecting from said metal member between said walls, directing a third jet against said tongue in said heated area and moving said third jet in conjunction with said pair of jets so as to consume said tongue as it is formed.
4. A method of burning a slot in a metal member which consists in heating a given area of said member, burning individual slots in said heated area to form the walls of the aforesaid slot and produce a tongue of metal projecting from said metal member between said walls, and consuming said tongue by burning, as said individual slots are being formed.
5. A method as set forth in claim 4 in which said tongue is consumed in said heated area.
6. The method of cutting a slot having inwardly and downwardly divergent side walls which comprises: heating the metal to be cut, directing against said metal two cutting jets which impinge on a line perpendicular to the axis of the desired slot to produce the angled side walls of said slot, directing a third cutting jet between said two cutting jets to attack the intermediate metal between said side walls, and moving all of said jets relative to said metal.
7. The method of cutting a slot having inwardly and downwardly divergent side walls which comprises: heating the metal to be cut, directing two relatively diverging cutting jets which impinge on a line perpendicular to the axis of the desired slot, directing an auxiliary cutting jet to attack the metal between said side walls, and moving all of said jets relative to said metal.
8. The method of cutting a slot having inwardly and downwardly divergent side walls which comprises: heating the metal to be cut, directing two diverging jets with their axes lying in a plane transversely disposed relative to the axis of the slot to form the side walls of said slot and a core of metal in the interior of said slot, directing a jet against said core and moving said last mentioned jet so as to closely follow said diverging jets at a fixed distance therefrom.

In testimony whereof, I have hereunto set my hand at Los Angeles, California, this 60 20th day of September, 1923.

CLARENCE J. COBERLY.
